UNITED STATES PATENT OFFICE.

JOHN G. REBER, OF CHICAGO, ILLINOIS, ASSIGNOR TO J. W. SEFTON MANUFACTURING COMPANY, OF ANDERSON, INDIANA, A CORPORATION OF INDIANA.

OYSTER-PAIL.

No. 886,074.

Specification of Letters Patent.

Patented April 28, 1908.

Application filed August 7, 1905. Serial No. 273,117.

To all whom it may concern:

Be it known that I, JOHN G. REBER, a citizen of the United States, residing at Chicago, in the county of Cook and State of Illinois, 5 have invented certain new and useful Improvements in Oyster-Pails, of which the following is a specification.

My invention relates to what are commonly known as oyster pails for the packaging 10 of oysters sold in bulk and the object thereof is to provide such a pail with simple and novel means for effectually preventing slopping of the contents, that is the escape more particularly of the liquid over 15 the top edges of and between the side walls of the pail.

Another object of my invention, as an incident to the provision of the anti-slopping means referred to, is to so cover the inner 20 ends of the bail of the oyster pail as to prevent the catching of one pail upon another when they are withdrawn from their nested condition.

In the drawings, Figure 1 is a perspective 25 of my oyster pail with the covers shown open; Fig. 2 a plan view of the blank of the pail; Fig. 3 another perspective of the pail with a portion broken away to expose my anti-slopping strip; Fig. 4 a plan view of 30 such strip; Fig. 5 a section on the line 5—5 of Fig. 3; Fig. 6 a view similar to that of Fig. 5, but illustrating a modified form of construction, as regards the attachment of the inner ends of the bail; and Fig. 7 a detail view of a modified form of construction 35 as regards the separate strip and corner folds representing a reversal in respect to the location of the slot 7^a.

My invention relates, as above stated, to 40 means for preventing slopping of the contents of the pail and such means are arranged to be embodied in any of the usual forms of oyster pails, a blank for the conventional form of which is shown in Fig. 2. The blank 45 of this form of oyster pail comprises a bottom 1, the four similar sides 2, the sets or pairs of triangular folds 3, 3, the top extensions or lids 4 and the corner extensions 5, 5. The blank is folded up in the usual and well 50 known manner, with the extensions left open or flaring, as seen in Fig. 1 and provided with a bail 6, whose ends are passed through the corner folds 3 and side walls 2 and turned back on the inside. In practice, these pails 55 are nested together and shipped to the con-

sumer in that form and are left in that condition by the consumer until the time of use. However, in oyster pails of this construction, the contents are liable to slop over the top edges of the two opposite side walls 2, which 60 are unprovided with the extensions or lids and to pass down between the outer side of such side walls and the corner folds thereby escaping and dripping from the pail.

The principal object of my invention is to 65 provide simple means for preventing this slopping, which means comprises a strip 7, illustrated in detail in Fig. 4, which strip is creased or hinged at its middle and adapted to be folded over the top edge of the two 70 plain side walls 2 of the pail and also to be folded or tucked down in the spaces between the walls of the corner folds, with the result that the slopping and escape of the contents of the pail in the manner described is effect- 75 ually prevented. At the same time, I obtain another useful result by the use of this anti-slopping strip, inasmuch as one of the portions or flaps of the strip which is secured, preferably by pasting, to the inner top ends 80 of the plain side walls 2, Figs. 1 and 3, covers the inner ends of the bail, Fig. 5, and thereby forms a smooth inner surface to the pail and avoids an objection to the bail, due to the fact that when the pails are nested together the 85 bail of one pail is apt to catch the pail about to be withdrawn and be liable to injure the latter. In order to permit of the proper folding and tucking of the other flap of the anti-slopping strip which is the lower one, as 90 viewed in Fig. 4, I provide such strip with a slot 7^a, which is an oblique one for the purpose of accommodating the particular oyster pail now being described and for accommo- 95 dating also the particular method of applying the strip to the pail. As illustrated more particularly in Fig. 3, this slotted flap of the strip is tucked between the faces of the plain side walls 2 and their corner folds 3, the larger portion 7^b being folded over the 100 top edge of its plain side wall 2 for a portion of its length and tucked down between the pair of corner folds on one side of the box, while the other or smaller portion 7^c of this flap is folded over the top edge of the remain- 105 ing portion of its side wall 2, and tucked down between the corner folds at the other side of the box. The slot 7^a permits this peculiar folding and tucking in, inasmuch as the slot accommodates the upper end of the 110

diagonal fold of the first mentioned corner folds. This strip not only accomplishes the two objects above mentioned, but also serves to strengthen the box, inasmuch as it 5 provides additional thicknesses of material, and also holds the upper ends of the corner folds into close relationship with respect to their side walls 2.

In Figs. 3 and 6 I have shown a modified 10 form of construction of pail, in which the ends of the bail or any part thereof are not passed through the side walls and corner folds, so as to be exposed on the inside of the pail, but are secured merely to the sets of 15 corner folds. In the particular instance shown, I attach staples 8, to such corner folds and loop or secure the ends of the bail thereto. According to this construction, the 20 anti-slopping strip 7 is tucked down between the pairs of corner folds as to one of its portions, but as to the other portion, the same may be folded over the top edge of its side wall and secured or pasted to the inner upper edge thereof in the same manner as in respect to the box of Fig. 1, but, if desired, such 25 portion of the strip may be folded or tucked down between the outer surface of its side wall and one of the corner folds on each side of the box, such portion of the strip being pasted on both of its sides so as to seal the 30 pail against the escape or leakage of its contents.

By the use of my strip I am enabled to 35 effectually seal a pail of the character described and thereby make it anti-slopping. Moreover, the strip can be economically made, being formed, in practice, from the waste or trimmings, resulting from the 40 stamping out of the blanks, besides which, the strip can be readily and quickly applied to the pail.

Although it is preferable to provide the slot in the separate strip in order that the latter may be properly positioned or tucked 45 between the corner folds, yet it is obvious that this strip may be made plain, that is the slot therein dispensed with and the slot provided in the top edges of the corner folds for the purpose of receiving one of the halves of 50 the strip and permit it to pass downwardly to occupy its proper position. Such modified form of construction and arrangement is illustrated in Fig. 7.

I claim:

55 1. In an oyster pail, the combination, with two of the opposite side walls thereof and

their pairs of corner folds, of strips formed separate therefrom and tucked between the members of the corner folds and engaging the upper ends of their respective side walls 60 whereby the space between the side walls and corner folds is sealed to prevent slopping of the contents of the pail; substantially as described.

2. In an oyster pail, the combination, with 65 two of the opposite side walls thereof and their pairs of corner folds, of strips formed separate therefrom tucked between the members of the corner folds and folded over upon and secured to the inner upper portion 70 of their respective side walls whereby the space between the side walls and corner folds is sealed to prevent slopping of the contents of the pail; substantially as described.

3. In an oyster pail, the combination, with 75 two of the opposite side walls thereof and their pairs of corner folds, of strips longitudinally creased to form two portions, one portion of each strip being folded over and secured to the inner upper ends of its side 80 wall and the other portion being tucked between the members of the corner folds corresponding to its side wall to seal the space between the walls and folds and thereby prevent slopping of the contents of the pail; 85 substantially as described.

4. In an oyster pail, the combination, with 90 two of the opposite side walls thereof and their pairs of corner folds, of strips longitudinally creased to form two portions, one portion of each strip being folded over and secured to the inner upper ends of its side wall and the other portion being transversely slotted and tucked between the members of the corner folds corresponding to its side 95 wall; substantially as described.

5. In an oyster pail, the combination, with 100 two of the opposite side walls thereof and their pairs of corner folds, of strips creased longitudinally to form two portions, one portion being folded over the inner upper ends of its side wall and the other portion being provided intermediate its length with an oblique open ended slot extending from one edge to said crease whereby said other portion may be tucked between the members of the corner folds and the corresponding side wall.

JOHN G. REBER.
